SWITCH

Fred C. Schwanek, Chicago, Ill., assignor to
Dormeyer Corporation, Chicago, Ill., a corpora-
tion of Illinois

Original application June 15, 1948, Serial No.
33,191. Divided and this application Septem-
ber 29, 1949, Serial No. 118,508

10 Claims. (Cl. 200—61.58)

1

This application relates generally to electric switches and more particularly to an improved nonarcing slow-acting switch which is closed only when two independent conditions have been fulfilled or, put another way, which opens if either of two separate control elements is actuated.

This application is a division of my application for Drink Mixer, Serial No. 33,191, filed June 15, 1948, and is related to my application for Switch, Serial No. 14,600, filed March 12, 1948. Reference to both of these applications is hereby made.

The switch of this invention has proved particularly useful in controlling the motor of an electrically powered drink mixer having a removable power transmission element. When used in this manner the switch performs the dual function of controlling the supply of current to the motor in response to a manual switch lever and of cutting off the supply whenever the transmission housing is removed.

Accordingly, one object of this invention is to provide a novel control switch for a drink mixer which prevents the motor's being energized except when the power transmission is connected thereto, and which serves as the sole motor control switch, being actuatable by a manually driven control member.

Another object is to provide a single switch which performs the function of two switches connected in series, and which is nonarcing even when opened or closed slowly under a heavy direct or alternating current load.

Another object is to provide a switch in which the contact points are enclosed in a hollow sleeve which excludes oxygen therefrom and reduces arcing, the contact points being open to the atmosphere while the switch is closed and sealed therefrom during the opening of the contacts and after they are opened.

Other and additional objects and advantages of this invention will present themselves to those familiar with the art on reading the following specification in conjunction with the drawings and the appended claim.

In the drawings:

Fig. 1 is a side view, partially in section, of a mixer provided with the switch of this invention;

Fig. 2 is a top view of the mixer with the transmission housing removed to show the switch;

Fig. 3 is an enlarged view showing the control switch of this invention;

Fig. 4 is an enlarged partial section showing

the disposition of the switch within the mixer, the transmission being removed and the switch being in the open position;

Fig. 5 is a view similar to Fig. 4 showing the position of the various switch elements when the transmission housing is in place and the switch knob is in the "on" position; and

Fig. 6 is a view similar to Fig. 5 showing the position of the switch elements when the transmission housing is in place and the switch knob is in the "off" position.

The construction and operation of the switch of this invention may be best understood if the drink mixer in which it has proved to be particularly useful is first described.

The mixer 10, as shown in Fig. 1, comprises a casing 11, a transmission housing 12, and a glass mixing cup 13. The casing 11 is preferably formed by die casting and consists of a base portion 14 and a hollow upright motor containing portion 15. The top side of the base portion 14 is cut away to form a platform on which the mixing cup 13 rests. The housing 12 is formed of two pieces of metal, a cover member 17 and a base plate 18 which is received on the upper end of the casing 11, the plate 18 extending over the top of the cup 13.

The agitator 20 comprises a shaft 21 journaled in the housing 12 and having impeller elements 22 and a disintegrator element 23 mounted on its lower end. The agitator 20 is described and claimed in my copending application for Drink Mixer Agitator, Serial No. 21,717, filed April 17, 1948.

A series wound motor (not shown) is mounted in a hollow within the casing 11. The casing 11 serves not only to house the motor 25 but also to support the individual elements of the motor in the proper relationship to one another. The upper end of the armature shaft 30 extends beyond the top of the casing 11, and is provided with a spring (not shown) for engaging a rotatable sleeve 53 journaled in the plate 18 in drive relationship.

A lower portion 18 of the housing 12 is substantially in the form of a flat plate having downwardly extending projections thereon. One of these projections 47 has a circular periphery and sets snugly into the top of the casing 11 to hold the housing 12 in the proper position when it is mounted upon the casing 11. A key and keyway (not shown) integrally formed on the plate 18 and the top of the casing 11 serve to prevent rotation of the housing 12 from the proper position with respect to the casing 11. The cen-

tral part of the projection 47 is provided with a hole receiving a bearing member 50.

Two pulleys 55 are mounted on the upper ends of the sleeve elements 52 and 53, the sleeves 52 and 53 being pressed into the pulleys 55 so as to be fixed thereto. The belt 46 runs on the pulleys 55 and is preferably formed of rubber or other elastic material so that a tensioning adjustment need not be provided. The upper end of the sleeve 53 is provided with two slots (not shown) cut at right angles to each other so that the agitator and the motor shaft need only be rotated through 90° until the spring element (not shown) springs outwardly into one of the slots to lock the motor shaft to the sleeve. Thus the spring serves the dual function as a key-way for preventing rotation of the shaft independently of the sleeve and as a locking element which tends to hold the shaft in the sleeve unless sufficient force is exerted to overcome the spring tension.

From the foregoing it will be seen that all that need be done to remove the transmission housing 12 from the casing 11 is to pull upwardly on the housing 12 causing the end of the spring to move inwardly so that the sleeve 53 may be slipped off the shaft 30. Thus the spring also serves to hold the housing 12 tightly against the top of the casing 11.

The control switch 60 is similar in some respects as that shown in my copending application for Switch, Serial No. 14,600, filed March 12, 1948.

However, the switch of this invention performs an additional function over that disclosed in my copending application and although somewhat similar in appearance differs in its operation.

The location of the switch 60 within the mixer 10 is best shown in Figs. 1 and 2. The switch 60 is attached to an insulating bracket 61 which is in turn secured to the casing 11 by a pair of screws 62, a recessed portion 63 being provided in the casing 11 in order that the switch 60 may be disposed in the proper position.

The switch 60 is manually actuated by rotation of a cam 64 attached to the end of the shaft 65 journaled in the wall of the casing 11, a knob or lever 66 being attached to the outer end of the shaft 65. A spring detent 68 in the wall of the casing 11 serves to hold the knob in either the "off" or "on" position.

The construction of the switch proper 60 is best shown in Fig. 3. The switch 60 comprises a base plate 70 of insulating material, an insulating spacer 71, a pair of contacts 72 and 73 and two resilient members 74 and 75 fixed to the spacer block 71. The lowermost contact 73 is supported on the member 70, being separated therefrom by an insulating spacer 76, the lower end of the contact 73 projecting through the spacer 76 and the member 70 and being peened over as indicated at 77 to hold the contact 73 rigidly to the member 70. A terminal lug 78 is in contact with the peened over portion 77 and thereby is electrical-ly connected to the contact 73.

The upper contact 72 is attached directly to the member 74. The resilient member 74 is bent so as to tend to carry or move the contact 72 to the position of rest shown in Fig. 4 when unstressed.

The lowermost resilient member 75 extends beyond the end of the member 70 and is provided with a hole 81 through which the contacts 73 and spacer 76 extend. When the knob 66 is rotated to the position shown in Fig. 6, the member 75 which normally lies against the member 70 is

forced upwardly to the position as shown in Fig. 3 carrying with it an insulating sleeve 83 which transmits its motion to the member 74 and serves to move the member 74 and contact 72 upwardly. When the knob 66 is turned to the position shown in Fig. 5 the cam 64 is rotated 180° and allows the member 75 and sleeve 83 to move downwardly to the position shown in Fig. 4.

To actuate the switch 60 when the housing 12 is in place, a piston-like member 85 is provided in the plate 18 to support this member, and an opening 86 is provided in the plate 18 from the upper end thereof, a hole 87 extending from the bottom of this opening through the plate 18. The member 85 is rod-like in form, having a larger diameter upper portion 88 which normally rests against the bottom of the cavity 86. A spring 90 tends to force a member 85 downwardly to the limit of its travel and a setscrew 91 received in the top of the opening 86 supports the upper end of the spring 90 and also provides a means for adjusting the tension. The end of the member 85 projects from the bottom of the plate 88 and, when the housing is in place, serves to force the member 74 and the contact 72 downwardly to the position shown in Fig. 5, providing the knob 66 is in the "on" position.

When the knob 66 is rotated to the "off" position, the various elements are disposed as shown in Figs. 3 and 6, the member 75 being moved upwardly lifting the sleeve 83 and the member 74, the spring 90 being compressed as the member 85 moves upwardly, the contacts 72 and 73 separating.

When the knob 66 is in the "off" position as shown in Fig. 6, and the housing 12 is lifted off the casing 11, the various elements assume the positions shown in Fig. 4, the member 74 springing upwardly as the member 85 is lifted away and the contacts 72 and 73 separating to open the circuit as the member 74 is free to move upwardly.

The switch 60 is connected in one of the line conductors (not shown) of the motor. Thus when the switch is open, the motor is deenergized and when it is closed is energized, no additional switches being required.

Since the switch of this invention may be opened slowly if the knob 66 is turned slowly or if the housing is removed slowly, its contacts 50 might be likely to arc and deteriorate except for the snuffing action of the sleeve 83 which serves to rapidly extinguish any arc formed in the manner described in my copending application referred to above.

From the foregoing description it will be readily apparent that a superior switch having several novel features which may be readily adapted to other types of switches has been provided. Furthermore, the switch of this invention may be put to many other uses than in a drink mixer as described herein.

Various changes and modifications such as will present themselves to those familiar with the art may be made in the embodiment described without departing from the spirit of the invention whose scope is defined by the following claims.

What is claimed is:

1. A switch for use in a food mixer having a casing enclosing a motor and a transmission housing element removably attached thereto, said switch comprising a resilient member supported on said mixer casing, a movable contact 70 on said resilient member, a second contact co-

operating with said movable contact, means on the transmission housing element for urging said resilient member toward said second contact when the element is attached to said casing, and manually actuated means for separating said two contacts.

2. A switch for use in a food mixer having a casing element enclosing a motor and a transmission housing element removably attached to said casing element, said switch comprising a resilient member, a movable contact on said resilient member, a second contact cooperating with said movable contact, means on one of said mixer elements for urging said resilient member toward said second contact when said housing element is attached to said casing element, and manually actuated means for separating said two contacts independently of the relative position of said elements.

3. A switch for use in a food mixer having a readily removable transmission housing, said switch comprising a supported contact, a movable contact, a resilient member supporting said movable contact and tending to move same away from said supported contact, yieldable means carried by said housing for urging said movable contact toward said supported contact when said housing is attached, and manually actuated means for separating said contacts against the force of said yieldable means.

4. A switch for use in a motor unit having a readily detachable transmission, and switch comprising a supported contact, a cooperating movable contact, resilient means for urging said movable contact away from said supported contact, an actuator member, an insulated sleeve enclosing said contacts, and a second resilient means supported by the transmission for urging said movable contact toward said supported contact, said second means overcoming the force of the first mentioned means, and motion of said actuator member being transmitted through said sleeve to separate said contacts by overcoming the force of the resilient means supported by said transmission.

5. A switch for use in a food mixer having a casing enclosing a motor and a transmission supporting element removably attached thereto, said switch comprising a resilient member supported on said casing, a movable contact on said resilient member, a supported contact cooperating with said movable contact, means on the transmission supporting element for urging said resilient member toward said supported contact when the element is attached to said casing, a sleeve enclosing said contacts, and manually actuated means for urging said sleeve away from the supported contact to separate the contacts.

6. A switch for use in a food mixer having a casing element enclosing a motor and a transmission housing element removably attached to said casing element, said switch comprising a resilient member, a movable contact on said resilient member, a supported contact cooperating with said movable contact, means on one of said elements of the mixer for urging said resilient member toward said supported contact when said housing element is attached to said casing element, and manually actuated means for separating said two contacts independent of the relative position of 70 said elements.

7. In a switch, the combination including a supported contact, a cooperating movable contact supported on a resilient member, said member being biased so that said movable contact normally rests at a point spaced from said supported contact, resilient means for moving said movable contact to a position where it is engageable by said supported contact, a loose fitting sleeve member surrounding said contacts, a second member surrounding the base of said supported contact for bearing against one end of said sleeve member, and manually operated means for moving said second member in the direction of said movable contact, motion of said second member being transmitted through said sleeve to said movable contact to separate said two contacts in the event they are touching.

8. In a switch, the combination including a supported contact, a movable contact, a resilient member supporting said movable contact, said member being biased to normally move same away from said supported contact, yieldable actuator means for urging said movable contact toward said supported contact, and manually actuated means for separating said contacts against the force of said yieldable means.

9. A switch comprising a supported contact, a cooperating movable contact, resilient means carrying said movable contact and normally urging said movable contact away from said supported contact, an insulated sleeve enclosing said contacts, and a second manually controlled resilient means for urging said movable contact toward said supported contact, said second means being of such strength as to overcome the force of the first mentioned means when operative, and a separate manually controlled actuator member for transmitting motion through said sleeve to separate said contacts by overcoming the force of said second resilient means.

10. In a switch, the combination including a supported contact, a cooperating movable contact carried by a resilient member, said flexible member being outwardly biased and tending to move said movable contact to a position away from said supported contact, a loose fitting sleeve member surrounding said contacts, an actuator surrounding the base of said supported contact and bearing against one end of said sleeve member, manually operated means for moving said actuator toward said movable contact, motion of said actuator being transmitted through said sleeve to said resilient member to move said movable contact away from said supported contact, and manually controllable yieldable means for overcoming the flexure force of said resilient member to cause said contacts to meet, said yieldable means yielding when said actuator is moved.
